UNITED STATES PATENT OFFICE.

WILLIAM I. BALLENTINE AND PAUL R. THOMPSON, OF LA PORTE, INDIANA, AS
SIGNORS TO ADVANCE-RUMELY COMPANY, OF LA PORTE, INDIANA, A CORPORA-
TION OF INDIANA.

REIN GUIDE.

Original application filed June 16, 1923, Serial No. 645,751. Divided and this application filed June 25, 1923. Serial No. 647,608.

The present invention relates to rein guiding means for rein controlled devices such as tractors.

This is a division of copending application Serial No. 645,751, filed June 16, 1923.

Among the objects of the invention are to provide a rein guide for guiding a rein about a corner or angle and which will accommodate itself, automatically, to the direction of pull on the rein; to provide such device with means, such as a pulley, for guiding of the rein about the desired angle and with means for swivelling the guiding means in accommodation of the direction of pull on the rein; to enclose the guided portion of the rein in order to exclude the entry of foreign matter, such as dust, mud, rain and other and similar matter; to provide the guides with cleaning means, such, as wipers, which preferably surround the reins as they enter the guides and maintain the reins neat and clean; to connect the guides to the housing of the control mechanism of the tractor so that all parts are enclosed, the wipers on the guides and about the reins completing the enclosing feature thereof; and such further objects, advantages and capabilities, as will later more fully appear and are inherently possessed by the invention.

In the drawings illustrating a preferred embodiment of the invention, Fig. 1 is a top plan view of a tractor embodying the invention; Fig. 2 is a vertical sectional view through one of the guides and a part of the control mechanism for the tractor; Fig. 3 is a top plan view of guides constructed in accordance with the invention; Fig. 4 is a rear elevational view of the same, the reins being shown in section; Fig. 5 is a vertical sectional view through the guides and part of the housing for the control mechanism, showing the swivel action of one of the guides, and Fig. 6 is a transverse sectional view through the wiping part of a guide.

Referring now more particularly to the drawings, the invention is shown as embodied in a tractor comprising a power plant 1, preferably of the internal combustion type, supported upon a pair of bull wheels 2 rotatably mounted at the outer ends of a pair of axle housings 3 rigidly

fastened or secured to the sides of the engine frame or block by any suitable means, as by bolts 4. At the rear end of the engine 1 is rigidly attached a housing 5 within which is located the power transmitting means and the control mechanism therefor, for the driving of the wheels 2. At the rear end of the housing 5 is attached a hitch mechanism 6 to which are connected reaches 7 and 8 of a drawn implement suitably supported upon an axle 9 and wheels 10 and 11 as clearly shown in Fig. 1 of the drawings. A seat 12 for the driver or operator may be supported by any suitable means 13 fastened to the drawn implement, a pair of reins 14 and 15 extending from the mechanism in the housing 5 to the seat 12 where they may be manually operated by the driver on the seat. These reins extend to and through rein guide mounted upon the upper wall of the housing side.

Each rein guide comprises a casing having two sections 16 and 17 with the latter rotatably fitting within the former so as to form a sort of angular telescopic connection or swivelled assembly whereby the section 17 is capable of movement about a horizontal axis with respect to the section 16, as clearly shown in Fig. 2 of the drawing. The section 16 has a lower tubular member 18 rotatably fitting in a hub portion 19 of the casing 5. The section 17 has a tubular extension 20 in which is located a wiping material 21, preferably a fibrous material, surrounding the reins 14 or 15 entering the member 20. It will thus be seen that the members 16 and 17 together with the tubular members 18 and 20 form a hollow passage for the passing therethrough of the rein into the casing 5. The tubular member 18 is rotably mounted in the hub 19 so that the guide, as a whole, may rotate or swivel about a vertical axis of the tube 18 in order to accommodate the position of the guide member to the direction of pull on the rein. This is clearly shown in Fig. 5 of the drawing at the right hand side thereof. This action is automatic and is freely effected irrespective of direction of the pull on the rein, the tubular member 20 always following the angular movement of the rein and causing the guide to turn about the axis 100 of the tube 18. When a tractor rides over

105

rises and into depressions there will also be an upward and downward movement of the rein with respect to the tractor and the section 17 together with the tubular member 20 will also have an up and down movement about the horizontal axis of the connection between the section 16 and 17, in accommodation with the movement of the rein.

In order to guide the rein about a corner or angle, from a horizontal to a vertical, so that the inner end of the rein may run properly to the control mechanism, each guide is provided with a flanged pulley 22 rotatably mounted upon a transverse shaft 23 carried by the section 16, the outer ends of the shaft 23 being preferably threaded to receive clamping nut 24. The section 17 is preferably formed with bearings 25 rotatable upon the shaft 23.

The wiping means in the tubular member 20 is preferably formed of fibrous material surrounding the rein 14 and is held in place by means of projections 26 formed in the inner part of the tube 21 the fibrous material being preferably confined between the projections 26 which are spaced from each other as clearly shown in Fig. 2 of the drawing. This fibrous material surrounds the rein rather closely so that as the latter is caused to slide or move longitudinally thereof through the fibrous material, the latter will constantly act to maintain the rein neat and clean and also prevent the entry of dust, rain, mud and other foreign matter into the interior of the guide, and hence the casing 5. The outer end of the tube 21 is preferably flared to form a belled portion 27 for the ready entry of the rein. The projections 26 are located opposite sides of the reins and pairs with the projections of each pair opposite each other and they extend inwardly substantially close to the surfaces of the reins so that the space between the inner ends of the projections of each part forms a slot or guiding opening for the rein, the opening being substantially, but slightly greater than, the thickness of the rein.

Within the casing 5 is included the transmission mechanism for controlling the driving of the wheels of the tractor and control members, such as rein drums 28 carrying cams 29 and 30 operably connected with suitable means for controlling the transmission mechanism. The inner end of each rein is suitably connected to a rein drum in any manner desired. The rein drums are rotated in one direction by a pull upon the reins, and suitable springs are provided for rotating the drums in the opposite direction, at which time the reins are drawn forwardly in a direction opposite to that when the operator pulls on the reins.

Should the tractor be driving at an angle with the driven implement, such as around a curve or toward a cramped position, the

direction of pull on the rein would be at an angle to the longitudinal line of travel of the tractor, and the guide members will swing about the vertical axis of the tube 18 in accommodation with the direction of pull of the rein. This occurs freely and automatically without any other action upon the part of the operator.

While we have herein described and shown upon the drawing a preferred embodiment of the invention, it is to be understood that the invention is not limited to the particular construction, details and arrangement of parts shown and described, but that other constructions, details, and arrangements of parts are comprehended by the invention without departing from the spirit thereof.

Having now described our invention, we claim:

1. A rein guide comprising a casing through which the rein passes, a guide member in the casing for guiding the rein around an angle, means swivelly supporting the casing in accommodation of the direction of pull on the rein, said casing comprising sections for housing the rein passing to and from said guide member.

2. A rein guide comprising a casing having swivelled sections, a guide member in the casing for guiding the rein about an angle, one of said sections being movable in accommodation of the direction of pull of the rein.

3. A rein guide comprising a casing having swivelled sections, a guide member in the casing for guiding the rein about an angle, one of said sections having wiping means for maintaining the rein neat and clean.

4. A rein guide for guiding a rein to the controlling mechanism of a tractor, comprising a pulley over which the rein may be guided, means supporting the pulley for rotation about an axis, a rotatable mounting for the supporting means for rotation about an axis transverse to the axis of the pulley, and a guide member rotatably mounted on the mounting whereby the guide member is universally movable in accommodation of any angular movement of the rein.

5. A rein guide comprising a casing having swivelled sections, a guide member in the casing for guiding the rein about an angle, means swivelly mounting the casing in accommodation of the direction of pull of the rein, one of said sections having means for maintaining the rein neat and clean.

6. A rein guide comprising a casing having swivelled sections, a guide member in the casing for guiding the rein about an angle, means swivelly mounting the casing in accommodation of the direction of pull of the rein, one of said sections carrying a cleaning wiper for maintaining the rein neat and clean.

7. A rein guide comprising a casing hav-

ing swivelled sections, a pulley rotatably mounted in the casing and operable to guide the rein about an angle, one of said sections having means for maintaining the rein neat and clean.

8. A rein guide comprising a casing having swivelled sections, a pulley rotatably mounted in the casing and operable to guide the rein about an angle, one of said sections having a passage through which the rein passes and means in the passage for maintaining the reins clear of foreign matter as the rein passes through said passage.

9. In a tractor having a movable control member and a housing therefor, a rein connected to the control member, a rein guide on the casing for the passage of the rein to

and from the housing, said guide being movable relative to the casing in accommodation of the direction of pull of the rein.

20

10. In a tractor having movable control members and a housing therefor, reins connected to the control members, hollow rein guides connected to the housing and through which the reins pass, swivel mountings for the guides whereby they will turn in accommodation of the direction of pull on the reins, and means in the guides for shutting out entry of foreign matter and maintaining the reins neat and clean.

30

In witness whereof we hereunto subscribe our names to this specification.

WILLIAM I. BALLENTINE.
PAUL R. THOMPSON.
